UNITED STATES PATENT OFFICE.

BERTIE E. MILLS, OF OAK PARK, ILLINOIS, ASSIGNOR TO MILLS NOVELTY COMPANY,
OF CHICAGO, ILLINOIS, A CORPORATION OF ILLINOIS.

TREMOLO DEVICE.

Application filed March 24, 1926. Serial No. 96,983.

This invention relates particularly to a sector 1^a of the corresponding lever and is adjustably secured to the lever by an adjusting device 1^b. The adjustment of strings, levers and springs is such that the strings are under normal tension with the 60 levers in horizontal position; and the springs preferably are at an angle of 45° with relation to the plane of the levers. It

5 The primary object is to provide an improved means for producing tremolo effects in machines of the character mentioned.

The invention is illustrated in a preferred embodiment in the accompanying drawings, 10 in which—

Fig. 1 represents a broken elevational view of string-tensioning means and pulsating-means connected therewith; Fig. 1^a, a fragmentary view of one of the tensioning-levers 15 shown in Fig. 1; Fig. 2, a broken plan view, partly in section, of the improved pump device and pulsating-means; and Fig. 3, a broken vertical section taken as indicated at line 3 of Fig. 2.

20 The views may be regarded as somewhat diagrammatic in their nature.

In the construction illustrated, A designates the neck-portion of a violin, for example, which is equipped with strings 1; B, 25 tensioning-means for said strings; C, pulsating-means associated with said tensioning-means and comprising individual pulsating-devices for vibrating each of the several tensioning-levers; D, pumping-means 30 actuated by a solenoid D' and provided with a conduit D² which serves all of the pulsating-devices; D³, a circuit-controlling device associated with the pump D; E, a manually-adjusted valve controlling the conduit D²; 35 E', an electro-magnetically controlled valve also controlling the conduit D'; and F, an electro-magnetic device, controlling the valve E'.

The normal tension of the strings 1 is applied through the tensioning-means B comprising, in the illustration given, a series of individual tension devices, each of which 40 consists of a tension-lever connected with the corresponding string, and a coil-spring of

45 adjustable tension. There are four tension-levers corresponding with the four strings of a violin. Two of the levers, designated 2 and 3, are seen in Fig. 1. They have pivotally connected therewith links 2^a and 3^a. 50 The springs 4 (one shown) are connected at one end by means of such links with the individual levers. At the other end the springs are connected with individual tension-adjusting devices 5 (one shown).

55 Each string 1 passes freely over a grooved

The pulsating-means C comprises a cylinder 6 and a piston 6^a for each tensioning-lever. The piston-rods shown are designated 6^b. It will be noted that in the case of the longer lever 3 the connecting rod is pivotally joined to the extremity of the lever at 7, while the link 3^a is pivotally joined 70 to the lever at 8. In the case of the lever 2, both the link 2^a and the connecting-rod are connected with the lever by a pivot-pin 9.

It may be noted here that the pistons 6^a need not fit closely within the cylinders 6. 80 The cylinders are served with compressed air, or air-pulsations, through individual conduits 10 extending through a block or valve-casing, 10^a fitted with controlling valves 10^b. The ports 10 are served from a common conduit 11, which is, in effect, a continuation of the conduit D² leading from the pump D. It is desirable that the tensioning-levers be vibrated rapidly to produce the desired tremolo effect, but the amplitude of movement of each lever preferably is suited to the corresponding string. The low string, for example, requires greater tension-variation than the high string. 85 The amplitude of movement and (if desired) the rate of vibration may be varied to accomplish the desired result.

The valves 10^b may be used to regulate the admission, or feed, of air-pulsations from the common conduit 11 to the several pulsating-devices. Thus, notwithstanding a single pumping mechanism serves all the pulsating devices, each pulsating device may be regulated to impart the vibrations suited to its particular lever and string.

Again, the valve E may be set to approximately regulate the feed to the conduit 11, and the valve E' may be controlled by a switch located at any desired point, as for example on a console fitted with a key man-

ual. Thus, the valve E' may serve as an auxiliary valve, conveniently controlled from any point, to vary the feed of air through the conduit D² to the passage 11, at will.

The pump D preferably is actuated by an electro-magnetic device. The preferred construction and arrangement is illustrated as comprising a cylinder 12; a plunger 13 fitted with a piston 13^a; the solenoid D' encircling or wrapped on the cylinder 12; and a coil-spring 14 which serves to retract the piston after it has been actuated by the solenoid D'.

15 The walls of the cylinder 12 may be of non-magnetic material, if desired. The plunger 13 and piston 13^a serve as a magnetic core, or plunger. The parts should be suitably designed to enable the solenoid to actuate the piston during its working stroke, i. e. in moving to the left-hand end of the cylinder as shown in Fig. 3. During this working stroke air is forced in regulated quantity through the outlet port 15 (Fig. 2), past the valves E' and E into the conduit D² and thence to the pulsating-means C. During the working-stroke of the piston, the tension of spring 14 is increased and later the spring retracts the piston.

20 30 The left-hand end of the plunger 13, designated 13^b, may be of brass or other non-magnetic material.

35 The plunger 13 has a projecting end-portion fitted with a flange 13^c which serves to actuate the circuit-controller D³ which controls the circuit 16 of the solenoid D'. The circuit 16 may be equipped, also, with a switch 16^a which may be located at any convenient point.

40 In the example given, the solenoid D' actuates the pump-piston in one direction and places the spring 14 under sufficient tension to retract the piston after the solenoid is de-energized. With such arrangement and operation, the piston, as it approaches the end of its working stroke, throws the switch D³ to circuit-breaking position, and when the piston is retracted the switch is again thrown to the circuit-closing position.

45 50 As shown, the switch D³ is mounted on a pivot 17 and is equipped with actuating arms 18 and 19 adapted to be engaged by the flange 13^c. The switch has a contact-arm 20 which co-acts with a contact point 21 with which the circuit 16 is provided.

55 The valve E' is normally open, or partially open. It has an actuating arm 22 connected with the movable core 23 of the solenoid F. A compression spring 24 tends to hold the core 23 in the normally displaced position shown in Fig. 2. The solenoid is provided with a circuit 25 equipped with a switch 25^a which may be located at any suitable point. Thus, the switch may be at a point remote from the solenoid and the valve

E' may be controlled therefrom. By closing the circuit, the solenoid will be energized and caused to draw in the core 23, thus restricting or closing the passage at the valve E'.

70 From the description given, it will be understood that the invention provides for giving an improved tremolo effect in a very simple manner and by means of very simple and readily controlled mechanism.

75 Obviously, the solenoid D' can be made to actuate the pump-piston in one or both directions, as desired, the arrangement described being a preferred arrangement. In fact, any suitable electro-magnetic device 80 may be employed for actuating the pump-piston, the latter serving, in turn, to automatically shift the circuit-changer, as required.

85 In practice, it is preferred to give the piston 6^a a fairly close fit within the cylinders 6, and to so operate the pump device that it will pulsate air back and forth through the conduit D² as the piston of the pump device D reciprocates. Thus, when the piston moves to the left, as viewed in Fig. 3, air will be forced through the conduit D² into the passage 11 and serve to elevate the pistons 6^a; and when the pump-piston is retracted, the air recedes from the cylinders of the pulsating-device C, allowing the pistons 6^a to descend. The return movement of the piston 13^a of the pump device D may be regulated by providing the end of the cylinder with an air discharge passage 26 fitted with 90 a valve 27 for regulating the size of the discharge passage. Thus, the rate of the pulsations may be regulated by regulating the movement of the piston 13^a.

95 100 The foregoing detailed description has been given for clearness of understanding only, and no unnecessary limitations should be understood therefrom, but the appended claims should be construed as broadly as permissible, in view of the prior art.

105 What I regard as new, and desire to secure by Letters Patent, is:

110 1. In combination with a string-tensioning device of a stringed instrument of the viol class, a tremolo-device comprising a pulsating-device connected with said tensioning-device, a pump provided with a conduit serving said pulsating-device, a solenoid serving to actuate said pump, and an electric circuit for said solenoid controlled by said 115 pump.

120 125 130 2. In combination with a string-tensioning device of a stringed instrument of the viol class, a tremolo-device comprising a pulsating-device connected with said tensioning-device, a pump comprising a cylinder and a reciprocating piston, yielding means serving to actuate said piston in one direction, a solenoid serving to actuate said piston in the other direction, an electric circuit 130

for said solenoid, circuit-controlling means actuated by said piston, and a conduit leading from said pump and serving said pulsating-device.

5. 3. In combination with a pulsating-device for actuating a string-tensioning device, pumping means comprising a cylinder equipped with a solenoid, a pump-piston within said cylinder actuated by said solenoid, a conduit leading from said cylinder and serving said pulsating-device, an electric circuit for said solenoid, and circuit-controlling means actuated by said piston.

4. In combination with a pulsating-device 15 for actuating a string-tensioning device, pumping means comprising a cylinder equipped with a solenoid, a pump-piston within said cylinder actuated by said solenoid, a conduit leading from said cylinder 20 and serving said pulsating-device, an electric circuit for said solenoid, and an oscillating circuit-maker and breaker actuated in both directions by said piston.

5. In combination with a string-tensioning lever, a pulsating-device, a pump serving said pulsating-device and having a reciprocating piston, and an electro-magnetic device serving to actuate said piston and having a circuit controlled by the movements of said piston.

6. In combination with string-tensioning means and co-acting pulsating-means, a pump having a conduit serving said pulsating-means, a valve controlling said conduit, and an electro-magnetic device for actuating said valve.

7. In combination with string-tensioning

means and co-acting pulsating-means, a pump having a conduit serving said pulsating-means and having a reciprocating piston, a valve controlling said conduit, and electro-magnetic devices for actuating said piston and said valve.

8. In combination with string-tensioning means and co-acting pulsating means, a 45 pump having a conduit serving said pulsating-means and having a reciprocating piston, a valve controlling said conduit, an electro-magnetic device serving to actuate said piston and controlled by said piston, and an 50 independent electro-magnetic device controlling said valve.

9. In combination with string-tensioning levers and separate pulsating-devices connected therewith, valve-controlled conduits 55 leading to said pulsating-devices, and a pump serving all of said conduits.

10. In combination with string-tensioning levers and separate pulsating-devices connected therewith, valve-controlled conduits 60 leading to said pulsating-devices, a pump having a conduit serving all said first-named conduits, and a valve controlling said second-mentioned conduit.

11. In combination with string-tensioning 65 levers and separate pulsating-devices connected therewith, valve-controlled conduits leading to said pulsating-devices, a pump having a conduit serving all said first-named conduits, a manually adjusted valve guarding said second-mentioned conduit, and also an electro-magnetically controlled valve controlling said second-mentioned conduit.

BERTIE E. MILLS.
